UNITED STATES PATENT OFFICE.

JOHN M. ROHLFING, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

CAR-UNDERFRAME.

1,244,780.

Specification of Letters Patent. Patented Oct. 30, 1917.

Application filed January 15, 1916. Serial No. 72,238.

To all whom it may concern:

Be it known that I, JOHN M. ROHLFING, residing at St. Louis, Missouri, and being a citizen of the United States, have invented 5 certain new and useful Improvements in Car-Underframes, of which the following is a full, clear, and exact description, such as will enable others skilled in the art to which it appertains to make and to use the 10 same, reference being had to the accompanying drawings, which illustrate the preferred form of the invention, though it is to be understood that the invention is not limited to the exact details of construction shown 15 and described, as it is obvious that various modifications thereof will occur to persons skilled in the art.

In said drawings:

Figure 1 is a plan view of a portion of 20 a car underframe embodying the invention hereinafter described. The figure illustrates portions only of an end sill, a bolster, center and intermediate sills of wood together with means of connection hereinafter more 25 fully described, and it is to be understood that the parts illustrated are duplicated at opposite sides of the longitudinal center of the car and at opposite ends of the underframe as is common in car construction.

Fig. 2 is a vertical sectional view the section being taken on line 2—2 of Fig. 1.

Fig. 3 is a transverse sectional view the section being taken on line 3—3 of Fig. 2, looking in the direction indicated by the 35 arrow, *i. e.*, toward the end sill of the car.

Figs. 4 and 5 are vertical sectional views taken on lines 4—4 and 5—5, respectively, of Fig. 3 as indicated on said Fig. 3.

Figs. 6 to 9 inclusive are directed to a 40 modification of the invention in the form of a cast steel embodiment in which Figs. 6 and 7 are views corresponding to the disclosure in Figs. 1 and 2, respectively.

Figs. 8 and 9 are vertical transverse sectional views the sections being taken on 45 lines 8—8 and 9—9, respectively, of Fig. 7. Said Figs. 8 and 9 are combined, the left hand portion indicating the section on line 8—8 and the right hand portion indicates 50 the section on line 9—9.

Fig. 10 illustrates a plan view of a further

modification of the underframe, depicting a cast steel embodiment of the invention quite similar to that shown in Figs. 6 to 9 inclusive, and in which reinforced longitudinal 55 members in the form of rolled H beams are provided and adapted to connect the body bolsters at opposite ends of the car and also the cast reinforce pans hereinafter described.

Fig. 11 is a sectional view the section being taken on line 11—11 of Fig. 10.

Fig. 12 is a transverse sectional view the section being taken on line 12—12 of Fig. 11.

The usual reinforced car underframe commonly includes wood center sills with metal draft arms which latter are attached commonly to such wood center sills and the only connection of such draft arms to other longitudinal sills is ordinarily through the bolsters.

While wood center sills are not now as commonly employed in new construction as heretofore, some cars are being built with wood center sills and many cars are in 75 service so equipped. To provide means for reinforcing both the new and old cars is one of the objects of the present invention.

Where the draft arms are connected only to the center sills and bolsters such connection is at right angles to the buffing and pulling stresses of service and obviously is not the most efficient manner of distributing such stresses. Many forms of horizontal diagonal braces between center sills or draft 85 sills and intermediate or side sills have been provided but such braces have commonly been located above the line of draft and afford but slight assistance to the draft sills where the draft lugs for the draft gears are 90 attached and where strength is most required to meet modern conditions.

In the drawings disclosing the invention both structural steel and cast steel embodiments are illustrated.

In said drawings Figs. 1 to 5 inclusive illustrate the structural embodiment of the invention and Figs. 6 to 12 inclusive illustrate the cast steel embodiment thereof.

The preferred form of the invention 100 would depend upon whether the manufacturer were equipped to produce large sized

steel castings or to fabricate sheets and shapes such are readily obtainable in the open market.

In the structural form D indicates the draft arm which is illustrated as comprising a single pressed plate of rectangular pan shape with vertical web 1 and with integral flanges 1^a and 2 which may be formed by pressing although it is not essential that such flanges 1^a and 2 be integral as they may be formed by riveting angles to the metal forming the vertical portion or web of such pan.

This draft arm is secured to the end sill 3 by a through bolt 4.

A stiffening and connecting angle 5 is secured to the horizontal flange 1^a of the arm D by rivets and to the center sill 6 by bolts 7. Said angle serves to stiffen both members and to connect them.

A similar angle 8 is secured to the inside of the intermediate sill 9, *i. e.*, on the side of the sill next adjacent center sill 6 and the horizontal leg of said angle extends toward the center sill.

Extending obliquely upwardly from and connected to the lower part of the draft arm is a plate 10 which is riveted to the horizontal leg 11 of angle 8. This plate is preferably substantially co-extensive in length with the draft arm, extending practically from the bolster to the end sill, so as to brace and reinforce the draft arm within the zone of the draft lug hereinafter referred to.

The plate 10 is provided with openings 12 to afford ready access to the bolts 7 and 7^a and said openings do not materially weaken the general structure.

Immediately back of the end sill 3 and resting above the plate 10 is a pressing 13 provided with horizontal and vertical flanges adapted for connection respectively with the angles 5 and 8 and center and intermediate sills before identified.

It is obvious that if such formation were desirable, the angles 5 and 8, plate 10 and sill pressing 13 might all be combined in a single pressing, providing the manufacturer were equipped for its production but there is an advantage in the combination of the plates and shapes referred to, in that they may be secured in the open market and fashioned without the employment of the large presses which would be required to form a single pressing.

It is to be noted that the angles 5 and 8 overlap, and are riveted directly to the top cover plate C of the bolster B.

A draft lug 15 of any type may be riveted or otherwise secured to the draft arm D and for convenience I have illustrated the draft arm of Ellis Patent No. 1,042,416 so connected.

In service the lateral thrusts which result from draft gear operation are met by the plate 10 which braces the draft arm laterally where such bracing is most required. Longitudinal thrusts imparted to the draft lug and arm by the coupler and draft yoke are transmitted to two wood sills by the means provided instead of to only one such sill at each side of the center line of the car as heretofore and such sills are in the present instance reinforced and connected so as to jointly absorb buffing stresses.

The cast embodiment of the invention comprises a main web portion 16, draft stops 17, horizontal flange and web 18 and 19, respectively, and vertical flanges 20 and 21 all cast as an integer so combined and adapted for connection with wood center and intermediate sills of a car as to connect and reinforce such sills and to compel cooperative action of such sills in resisting buffing and pulling stresses due to service conditions.

It will be noted that the horizontal web 19 with the integral vertical flanges 20 and 21 span the distance between the center sill 6 and the intermediate sill 9 with which the flanges 20 and 21, respectively, are connected by means of the bolts 7 and 7^a said web 19 and flanges 20 and 21 forming a reinforcing pan P which is adapted to assist the sills with which it is connected toward conjoint action in resisting buffing and pulling stresses.

The casting forming said pan extends inwardly, *i. e.*, toward the center line of the car, the web 19 terminating in the vertical main web portion 16 of a draft arm and draft lug combined which is formed integral with said pan.

Connecting said pan and draft lug at convenient intervals as required, are diagonal braces 27, two of which are shown for convenience of illustration.

Extended forwardly the pan is provided with a portion 22 forming a support for the buffer. The rear end of the vertical web portion is provided with flanges 23 and 24 that have vertical and horizontal portions and with a vertical flange 25 which are intended to and do bear against the top and bottom cover plates and the web of the bolster B, as will be best noted in Fig. 7.

Integral with the parts just noted, the combined draft arm and pan connector extends rearwardly, as shown at 26, (see Figs. 6 and 7) and hooks over the bolster at the rear of said bolster with which said extension 26 is connected by suitable rivets.

Integral with the parts referred to, is a shoulder 28 which rises vertically from the plane of the portion 19 of the casting and serves as a reinforce abutment at the rear or inner side of the end sill 3.

Thus far the cast metal embodiment of the invention has been described as applied to only one center sill and one intermediate sill but it is to be noted that four such connections are desirable, two of which occur at each end of the car.

It may be desirable to connect the sill reinforcements from end to end of the under-frame and for that purpose I prefer to em-

ploy a plurality of H shaped beams 29 which, as will be noted in Figs. 10 to 12 inclusive, are riveted to the bolsters and to the cast pan shaped connectors before referred to.

In this embodiment the beam is disposed with its web vertical and with its top and bottom flanges horizontal in which case the bottom flanges are riveted as before described and the top flanges may serve as supports for the flooring F of the car.

In Figs. 10 to 12 inclusive a casting 30 is shown as abutting the rear of the bolster B and is riveted directly to the bottom flanges of the H beam before referred to, thereby resisting any tendency of the bolster to ro-

tate about its longitudinal axis.

As in the structural form first described, the cast pan and draft arm distribute buffing shocks to a plurality of sills instead of to a single sill, meanwhile bracing both of the sills with which it is connected and providing a convenient and readily applied means for reinforcing wood or composite underframes of railway cars.

It is to be noted that neither form of the device necessitates the removal of any of the longitudinal sills or the floor of the car nor the dismounting or alteration of the bolster.

Also, the sills are connected by the pan-shaped members in segregated pairs.

What I claim is:

1. In combination, a bolster, a plurality of spaced sills, a horizontally disposed pan with vertical flanges paralleling and being connected directly to said sills thereby connecting them, said pan being removable without affecting said bolster, and a draft lug rigidly connected with said pan.

2. In combination, a plurality of spaced sills, a horizontally disposed pan with vertical flanges paralleling and being connected directly to said sills thereby connecting them, a draft lug vertically disposed and projected laterally away from said pan and an obliquely disposed brace uniting the pan and draft lug.

3. In combination, a plurality of spaced sills, a horizontally disposed pan with vertical flanges paralleling and being connected directly to said sills thereby connecting them, said sills not extending between said flanges, with an integrally formed draft lug and transversely disposed brace connected with said pan.

4. In combination in a railway car under-

frame, end sills, spaced wood sills extending between said end sills, a pan shaped member interposed between said sills and having pan flanges connected to and thereby connecting some of the sills without the so-connected sills being interposed between the pan flanges, and a draft lug connected with said pan.

5. In combination in a railway car under-frame, end sills, spaced wood sills extending between said end sills, a pan shaped member interposed between said sills and having flanges connected to and thereby connecting some of the sills, a draft lug positioned not to underlie the pan and paralleling some of the flanges of said pan, and a brace connecting a lower portion of the draft lug with a remote part of the pan.

6. In combination in a railway car under-frame, end sills, spaced wood sills extending between said end sills, a pan shaped member interposed between said sills and having flanges connected to and thereby connecting some of the sills and longitudinally disposed auxiliary metal sills connected to and connecting pans at opposite end portions of the car.

7. In combination in a railway car under-frame, end sills, spaced wood sills extending between said end sills, a pan shaped member interposed between said sills and having flanges connected to and thereby connecting some of the sills, bolsters connected with a plurality of said pans and a longitudinally disposed auxiliary metal sill lapping said bolsters and extending from bolster to bolster.

8. In combination, a plurality of spaced sills, and an integral casting comprising a horizontally disposed pan with vertical flanges paralleling and being adapted for connection directly to said sills to thereby connect them and a draft lug laterally removed from said pan and rigidly integral therewith.

9. As an article of manufacture, an integral casting comprising a horizontally disposed pan with vertical flanges adapted to parallel and be connected directly to car sills thereby to connect them, a ledge and a draft lug, a ledge integral with said pan extending from a side of said pan, vertically disposed and depending from the outer border of said ledge.

10. As an article of manufacture, an integral casting comprising a horizontally disposed pan with vertical flanges adapted for connection to car sills and thereby connecting them, said pan being formed with an integral draft lug and transversely disposed brace, said pan and draft lug being in different vertical zones.

11. In combination in a railway car underframe, end sills, spaced wood sills extend-

ing between said end sills, a casting provided with a non-sill-receiving pan interposed between said sills and having flanges connected to and thereby connecting some of the sills and a draft lug cast integral with said pan.

12. In a car underframe, a pair of pan-shaped sill-connecting and draft gear-supporting members at each end of said underframe and a plurality of pairs of sills

connecting said pan-shaped members, said members connecting segregated pairs of sills.

In witness whereof I have hereunto set my hand in the presence of two witnesses. 15

JOHN M. ROHLFING.

Washington, D. C."

It is hereby certified that in Letters Patent No. 1,244,780, granted October 30, 1917, upon the application of John M. Rohlffing, of St. Louis, Missouri, for an improvement in "Car-Underframes," an error appears in the printed specification requiring correction as follows: Page 3, strike out lines 110 to and including line 118, comprising claim 9, and insert the following as claim 9:

9. As an article of manufacture, an integral casting comprising a horizontally disposed pan with vertical flanges adapted to parallel and be connected directly to car sills thereby to connect them, a ledge extending from the side of said pan, and a draft lug integral with said pan vertically disposed and depending from the outer border of said ledge.;

and that the said Letters Patent should be read with this correction therein that the same may conform to the record of the case in the Patent Office.

Signed and sealed this 12th day of February, A. D., 1918.

[SEAL.]

J. T. NEWTON,
Commissioner of Patents.
